United States Patent Office.

JOHN BRYCE, OF EAST BIRMINGHAM, PENNSYLVANIA.

Design No. 3,759, dated November 23, 1869.

DESIGN FOR GLASS-WARE.

The Schedule referred to in these Letters Patent and making part of the same.

To all whom it may concern :

Be it known that I, JOHN BRYCE, of East Birmingham, in the county of Allegheny, and State of Pennsylvania, have invented a new and useful Design for Glass-Ware ; and I do hereby declare the following to be a full, clear, and exact description thereof, reference being had to the accompanying drawing, making a part hereof, in which—

Figure 1 represents my improved design, as applied to a fruit-dish ;

Figure 2 is a sectional view, through $x-x$, fig. 1 ; and

Figure 3 is an enlarged plan view of a portion of the raised work of the design more perfectly illustrating it.

Like letters of reference indicate like parts in each.

My improved design for glass-ware is entirely of raised work, and consists of a main vine or stem, a ,

branch stems c , leaf stems e , and skeletons of leaves i , all of prismatic shape, in cross-section ; that is to say, the parts named have an outer face, which corresponds in shape to two sides of prism. The leaves between the sections i are of raised roughened work, as shown at s .

Such design may be arranged on or applied to any and all bowed or hollow articles of glass-ware.

What I claim as my invention, and desire to secure by Letters Patent, is—

The design for glass-ware, herein described and shown.

In testimony whereof, I, the said JOHN BRYCE, have hereunto set my hand.

JOHN BRYCE.

Witnesses:

JOHN GLENN,
THOS. B. KERR.
